UNITED STATES PATENT OFFICE.

OLE ANDERSON, OF NEW SWEDEN, MINNESOTA.

MATCH-DELIVERING AND CIGAR-CUTTING APPARATUS.

SPECIFICATION forming part of Letters Patent No. 569,482, dated October 13, 1896.

Application filed November 12, 1895. Serial No. 568,675. (No model.)

To all whom it may concern:

Be it known that I, OLE ANDERSON, a citizen of the United States, residing at New Sweden, Nicollet county, Minnesota, have 5 invented certain new and useful Improvements in Match-Delivering and Cigar-Cutting Apparatus; and I do hereby declare the following to be a full, clear, and exact description of the invention, such as will enable 10 others skilled in the art to which it appertains to make and use the same.

My invention relates to improvements in match-boxes and cigar-cutters.

The object of my invention is to produce a 15 device particularly adapted for use in cigar-stores or other places where cigars are sold, which will perform the usual functions of a cigar-cutter and at the same time serve as a means for supplying matches, one at a time, 20 when properly manipulated.

My invention also comprises a novel construction of striking-block on which the matches may be lighted, and which block may be easily replaced when worn out.

25 With these objects in view my invention consists in the features, details of construction, and combinations of parts, which will first be described in connection with the accompanying drawings and then particularly 30 pointed out in the claims.

In the drawings, Figure 1 is a perspective view of a device embodying my invention. Fig. 2 is a longitudinal vertical section through the center of the match-compartment. Fig. 3 is a detail plan view of the delivering-slide and its attached mechanism. Fig. 4 is a detail sectional view of the cigar-cutter. Fig. 5 is a bottom plan view of the same. Fig. 6 is a detail perspective view of the striking-block clamp and the holder for the same in 40 their normal positions. Fig. 7 is a similar view showing the parts separated.

Referring to the drawings, A is a hollow base, divided into two compartments 1 and 45 2 by a partition a. Over the compartment 1 and on top of the base A is secured a match-box or match-delivering apparatus B, which has side walls b, a back b', and a front b'', which ends at a step b³, below which the box 50 is open. The side walls b are each provided with a downward and forward inclined rab-

bet b⁴, in which is placed a removable partition b⁵, which divides the match-delivering box into two compartments, the front of which I will call the "match-compartment," while 55 the rear one contains the match-delivering mechanism. At the foot of the inclined partition b⁵ is a horizontal movable match-delivering slide C, provided with a slot c of such a size as to hold one match loosely and yet 60 not large enough to hold more than one match. The normal position of this match-delivering slide C is such that the match-holding slot c will be at the bottom of the match-compartment and at the foot of the inclined partition 65 b⁵. The slide C extends forward beneath the front b², where it ends flush with a cross-bar D, beneath which is arranged a downward and forward sloping inclined plane E, preferably formed of a looking-glass. 70

The slide C, when moved forward by the mechanism to be hereinafter described, contacts with its front end against a strip b⁶, projecting downward from the step b³, in which position the match-slot c is beneath 75 the step b³ and forward of the cross-bar D.

For the purpose of moving the slide C back and forth it is provided with a cam-block F, secured to its rear edge and having a cam-surface f. The cam-block is also provided 80 with two holes f', into which project a pair of studs g, secured at their forward ends in a transverse brace G, fixed to the sides b immediately behind the bottom of the inclined partition b⁵, the front of said transverse brace 85 being sloped to correspond to that of the inclined partition b⁵. Between the cam-block F and the transverse bar G are placed springs H, arranged to press the cam-block rearward, these springs preferably being spiral and surrounding the studs g. The cam-surface f of the cam-block is engaged by the rounded surfaces i of a vertically-movable cam I, which slides in a recess k, cut in a guide-block K, secured to the sides b and the back b'. The 95 top of the cam-block I is provided with a plunger i', projecting through a hole l in a horizontal guide-plate L, whose ends are rabbeted into the sides b and whose rear end abuts against the back b'. This plunger i' is surrounded by a spiral spring i², whose lower end rests against the plate L, while its upper end 100

abuts against a head or collar i^3 , formed on the top end of the plunger. The said top end of the plunger is provided with a socket into which is inserted the lower end of a stem m , which projects through and is movable in a hole formed in a back lid b^7 , secured to the sides b over the rear compartment, the top of this stem m being provided with a push-button M , which projects some distance above the said lid b^7 . Said lid b^7 projects forward sufficiently to cover the top end of the inclined partition b^5 , whereby the latter is held in place firmly and may be readily removed by removing the lid b^7 to permit access to the operating mechanism in the rear compartment.

Beneath the slide C is a floor N , extending below the match-compartment and serving to prevent the matches from falling entirely through the match-receiving slot c , this floor N ending on a horizontal line with the cross-bar D , and preferably formed integral with the same.

The match-receiving compartment is closed by a lid b^8 , which may be hinged to the rear lid b^7 , but is preferably attached to it as follows: The front edge of the said rear lid b^7 is beveled downward and forward, while the rear edge of the front lid b^8 is correspondingly beveled to fit snugly to said rear lid. To the under side of the lid b^8 are secured two cleats b^9 , whose ends project slightly beyond the rear edge of the front lid and are adapted to project under the front edge of the rear lid b^7 , thereby holding the rear edge of the front lid from being lifted directly up. At the front of the lid b^8 and on top of the same is secured a suitable locking device engaging the front b^2 , which projects somewhat above said lid b^8 , the locking device in this case consisting of a button O , moving in a horizontal plane and pivoted on a screw o , secured in the lid b^8 , the button being provided with an upward-extending ear or thumb-piece o' , by which it may be operated and swung with its front end, which is pointed, as shown at o^2 , projecting into a groove o^3 , formed in the rear face of the front b^2 .

The operation of the mechanism thus far described is as follows: By swinging the button O so as to disengage its end o^2 from the groove o^3 in the front b^2 the front edge of the lid b^8 may be swung upward and the entire lid drawn forward until its cleats b^9 are removed from engagement with the back lid b^7 , after which the front lid may be removed and the match-compartment filled with matches, the front lid being then replaced. When it is desired to obtain a match, the button M is pressed downward, thereby forcing the cam I downward, as a result of which the cam-block F is engaged by the cam-surface i and crowded forward. When the match-compartment contains matches, the slot c in the slide C will be filled by a single match, and when, as above described, the cam-block F is forced forward the slide C , to which said block

is secured, will also be forced forward, and the single match contained in the slot, and which is held from dropping through the slot by the floor N , will be pushed along said floor until it arrives forward of the cross-piece D , whereupon it will drop out of said slot onto the inclined plane E , and will slide down to the forward and bottom end of said inclined plane, where it may be removed by hand, the match being stopped from sliding off the box altogether by means of a ledge P , which in this case is made ornamental and has a reduced central portion p to enable the fingers of the operator to readily grasp the match. On removal of the pressure from the button M the springs H and i^2 will return the parts to their normal position, thereby drawing the slide rearward until the slot c is again within the match-compartment, whereupon another match will drop into said slot ready for delivery at the next operation of the machine. In the compartment 1, beneath the match-delivering mechanism, is conveniently placed a drawer R , that may be used to hold several boxes of matches, if desired. Referring now to the cigar-cutting mechanism, which is arranged on top of the hollow base A over the compartment 2, it will be seen that this is at one side of the match-delivering mechanism, being secured to the door a^2 , forming a part of the top of said hollow base A . This door a^2 is provided with a plate S , let into the door a^2 and flush with the top of the same, the plate being provided with one or more holes s , s' , &c., preferably of varying sizes, to receive the ends of the cigars to be cut. The lid a^3 is provided with a dovetailed recess or rabbet extending below the plate S and forward to the front edge of the door a^2 .

T is a knife-block arranged transversely of the lid a^2 , and provided with an upward-extending dovetailed guide-piece t , to whose top surface is secured a knife t' , the knife t' moving in close contact with the bottom of the door a^2 , and in the recess within which the dovetailed guide-piece t also moves freely.

To the knife-block T are secured pins t^2 , which project through and are movable in holes u in a transverse cleat U , secured to the bottom of the door a^2 and below the rear edge of the plate S . Between said transverse cleat U and the knife-block T are arranged spring devices, in this case consisting of spiral springs V , surrounding the studs t^2 , the front ends of said springs abutting against the rear surface of the knife-block T , while the rear ends of the said springs bear against the front surface of the transverse cleat U , whereby the knife-block T , and with it the knife t' , are normally held forward. The front edge of the knife-block T is rounded, as shown, and is adapted to contact with a rearward-inclined abutment-block W , whereby as the lid a^2 is forced shut the knife-block T is crowded rearward by the resistance of the abutment-block W , and the knife t' is

moved across the openings s s' , thus clipping the ends off any cigar which is projecting through any one of said holes.

The tendency of the springs V being to force the knife-block forward, it results that when there is no pressure on the lid a^2 the latter is raised by the action of the inclined surface of the knife-block T on the abutment-block W . To prevent the lid from being thrown too far upward by the action of the springs V and knife-block T , the latter is provided with a tongue t^3 , projecting downward and forward and adapted to project beneath the abutment-block W , whereby the upward movement of the lid a^2 is limited, while at the same time by forcing the knife-block T rearward beyond its normal limit of play said tongue t^3 will be disengaged from the under side of the abutment-block W and the lid a^2 may be swung upward to permit inspection of or repairs to the cutting mechanism.

For the purpose of assisting the springs V in raising the lid a^2 an auxiliary leaf-spring X is provided, being secured to the base A , as shown, and bearing upward against the lid a^2 . As the lid a^2 normally stands slightly raised when not in use, I provide a downward-extending guard-plate Y , secured to the under side of the lid a^2 and projecting below or on a line with the bottom of the knife-block T , so as to prevent the entrance of dirt to the compartment 2.

Within the compartment 2 is placed a drawer Z , adapted to receive the ends which are cut from the cigars. The operation of the cutting mechanism is obvious from the description of the same thus far given.

Referring to Figs. 6 and 7, it will be seen that my improved match-striking device comprises a socket or holder A' , preferably formed from one piece of sheet metal having downward-projecting portions A^2 and outward-projecting ends A^3 , which are fastened by screws, nails, or otherwise to the top of the hollow base A . The holder is closed by a downward-projecting portion A^4 .

The clamp B' is formed from one piece of sheet metal stamped into the shape of a small box without a front and having the forward-projecting ends of its top and bottom bent to form open tubes B^2 or rolls. Within the clamp is placed a striking-block C' , fitting snugly within said clamp and provided with a roughened or corrugated surface C^2 , which is overhung by said tubes B^2 , referred to above.

The striking-block is preferably provided with a roughened surface on both its front and rear edges in order that when one edge has become worn too smooth for proper effect on the match-head the block may be taken out and turned with its worn edge rearward, thereby bringing a new roughened surface into action. The striking-block may be of metal or other material, but preferably of pottery-ware, and when so worn as to be

useless it may be readily replaced by a new striking-block. The clamp is held in the holder by the spring action of its tubes B^2 , one of which bears against the top surface of the hollow base A , and by its elasticity crowds the clamp upward against the top portion A' . By having the two tubes B^2 it is immaterial which way the clamp is placed in the holder, as there will always be one tube projecting downward into contact with the top of the hollow base A . Furthermore, since these tubes project forward of the corrugated or roughened surface of the striking-block C' , there is no trouble in striking a match on said striking-surface, since the match-head cannot slip off the roughened surface either downward or upward.

What I claim, and desire to secure by Letters Patent, is—

1. The combination with a match-box having a downward and forward inclined partition dividing the box into a match-compartment and a rear compartment, of a slide arranged below the match-compartment and provided with a slot, a cam-block secured to the end of the slide and within the rear compartment, a transverse bar, a pair of studs secured in said bar and passing loosely through the cam-block, a spiral spring surrounding each stud, said springs being between the bar and cam-block, a cam arranged to move at right angles to the slide, and in contact with the cam-block, a plunger to which said cam is fixed, a guide through which the plunger passes, a collar on the plunger, a spring surrounding the plunger, said spring bearing on the guide and against the collar, and a floor beneath the front end of the slide, substantially as set forth.

2. The combination, with a hinged lid provided with a dovetailed recess, a plate let into the lid and provided with holes to receive the cigar end, and a knife-block having a guide-piece movable in the dovetailed recess and provided with a downward and rearward inclined front surface, of a knife secured to said guide-piece and below the plate, a fixed abutment arranged to contact with the front surface of the knife-block, a transverse cleat secured to the under side of the lid and provided with holes, a plurality of pins fixed to the knife-block and movable in said holes, and springs intermediate the knife-block and transverse cleat, whereby the knife-block is pressed forward, substantially as set forth.

3. The combination, with a hinged lid provided with a dovetailed recess, a plate let into the lid and provided with holes to receive the cigar end, and a knife-block having a guide-piece movable in the dovetailed recess and provided with a downward and rearward inclined front surface, of a knife secured to said guide-piece and below the plate, a fixed abutment arranged to contact with the front surface of the knife-block, a transverse cleat secured to the under side of

the lid and provided with holes, a plurality of pins fixed to the knife-block and movable in said holes, springs intermediate the knife-block and transverse cleat, a downward-extending plate secured to the lid at one side, and a spring fixed at one end and bearing at its other end against the under side of the lid, substantially as set forth.

4. The combination, with a holder, of a clamp having the forward edges of its top

and bottom bent to form tubes, of a striking-block held by said clamp with its forward edge back of the said tubes, substantially as set forth.

In testimony whereof I affix my signature 15
in presence of two witnesses.

OLE ANDERSON.
